UNITED STATES PATENT OFFICE.

MARK K. BOWMAN, OF NEW YORK, N. Y., ASSIGNOR TO M. K. BOWMAN-EDSON COMPANY, OF NEW YORK, N. Y., A CORPORATION OF NEW YORK.

CLEANER FOR TUBES OF CONDENSERS, BOILERS, ETC.

1,424,336.

Specification of Letters Patent. Patented Aug. 1, 1922.

Application filed January 12, 1921. Serial No. 436,677.

To all whom it may concern:

Be it known that I, MARK K. BOWMAN, a citizen of the United States, and resident of New York, in the county of New York and State of New York, have invented certain new and useful Improvements in Cleaners for Tubes of Condensers, Boilers, Etc., of which the following is a specification.

10 My present invention is primarily concerned with apparatus broadly of the type for cleaning condenser tubes, that is, with apparatus of the type driven through the dirty tube preferably by the propulsive force 15 of compressed air, although water, or other liquid or gas may be used, the device having means for mechanically removing the mud or slime from the condenser tube, and driving the accumulation ahead of it as it is 20 propelled through the tube. The apparatus of my present invention is broadly of the same type as that of my Patent No. 1,325,348 issued December 16, 1919 and of my co-pending applications, Serial No. 397,574, 25 filed July 20th, 1920 and Serial No. 418,360, filed October 19, 1920 and can be used in substantially the same relations as the devices of said patent and applications for 30 cleaning either condenser or boiler tubes, although as heretofore noted it is preferably applicable to the cleaning of condenser tubes.

In common with my co-pending applications referred to, the present invention has for its object the provision of a tube cleaning projectile which shall be effective in its 35 action and inexpensive in its construction and which shall be susceptible of being formed in any sizes for use with tubes of any diameter, which shall be capable of turning 40 relatively sharp corners in tubes without likelihood of jamming, and which shall be particularly useful in cleaning tubes of the very small diameters.

According to one feature of the invention, 45 the projectile comprises a plurality of scraper elements coiled about the rod and disposed at uniform intervals along the length thereof, each said coiled element extending forwardly from the point at which 50 it is secured, in a helix of low pitch, the entire length of each scraper element being disposed between the adjacent scraper elements on opposite sides thereof, the successive scraper elements being identical in construction and in staggered relation with re-

spect to each other. Although I prefer to combine the features as set forth and superior results are obtained by such construction, it will be understood that certain of these features may be modified or omitted 60 without departing from the scope of my invention.

According to another preferred feature, each scraper element is formed of a unitary length of wire including an eye encircling 65 the rod and clamped in position about the rod by nuts threaded against opposite sides of said eye.

Referring now to the drawings in which is shown one of various possible embodiments of the several features of this invention,

Fig. 1 is a side elevation of a preferred form of cleaning projectile,

Figs. 2, 3, 4 and 5 are transverse sectional views taken along the lines 2—2, 3—3, 4—4 and 5—5 respectively.

Fig. 6 is a plan view of one of the scraper elements,

Fig. 7 is a side view thereof, 80

Fig. 8 is a perspective view of one of the nuts; and,

Fig. 9 is a side view of the supporting rod.

The views are all shown as of double the size of the smallest projectiles used in practice in order to better reveal the details of the construction.

Referring now to the drawings I have shown a projectile comprising a supporting rod 1 having threads as at 2 throughout the length thereof. A circular washer 3 of leather, cork or similar material and of somewhat larger diameter than the tube for which the projectile is designed is fitted over one end of the rod and nuts 4 and 5 threaded upon said rod and at opposite sides of the leather washer serve to clamp the latter in position, the free end of the rod being preferably upset as at 6 in order to secure the end nut against coming loose. 100

The scraping function of the projectile is preferably performed by a series of wire lengths extending circumferentially about the rod. By preference each scraper element 5 is formed of a length of round wire shaped as in Figs. 6 and 7, comprising an inner eye portion 7 to fit about the rod with a relatively snug fit having integral and continuous therewith a spirally shaped end 8 projecting outwardly therefrom to extend 110

about the rod for the major portion of one turn of materially larger diameter than the rod, and also bent out of the plane of the securing eye portion, as at 9, in a helix of 5 low pitch extending in the direction of the forward or advance end of the projectile. It will be understood that a single flat spiral may be employed, but I prefer the helical construction shown. The term "spiral" as 10 used in certain of the claims is to be considered generic to a flat spiral and a helix. A plurality of the scraper elements shown in Figs. 6 and 7, and of the circular nuts 10 shown in Fig. 8, are applied to the rod in 15 alternate relation, as shown in Fig. 1. As will be seen nut 10' is threaded against the end of nut 4, whereupon wire scraper S' is passed over the rod, followed by nut 10² thereby clamping the holding eye 7 of 20 scraper element S' securely in position between the adjacent surfaces of nuts 10' and 10². In a similar way the scraper elements and nuts are successively passed over the rod, the final nut 10 being secured by upsetting the end 11 of the rod thereover, or 25 by similar means. As best shown in Figs. 2, 3, 4 and 5 the wire scraper elements are placed in position in staggered relation. In 30 the specific embodiment shown, the free ends of the successive scraper elements are about ninety degrees apart although it will be obvious that the interval might be any other angle, if desired.

The pitch of the helical scrapers is preferably less than the thickness of nut 8, so that 35 no interference can take place between successive scraper elements, the entire length of each scraper element being disposed between the adjoining scraper elements. I 40 thus provide a projectile which though including a plurality of scraper elements is, nevertheless, of short length.

It is understood that the projectile will be made in different sizes to corresponding 45 with sizes of condenser tubes, the outside diameter of the helix being preferably approximately as large or somewhat larger than the tube to be cleaned thereby.

In use, the end 11 opposite the washer 3 50 is inserted into the condenser tube to be cleaned and the projectile will be urged forwardly by the use of compressed air or other fluid applied to the rear of washer 3. The length of each of the scraper elements 55 will undercut the accumulation of slime in its path, separating it from the walls of the condenser tube, each scraper element tending to slash through the mud or slime by reason of its spiral conformation. There 60 being no tendency to rotate the projectile about its axis, it will move with substantially a pure motion of translation and there will therefore be no tendency to spread or open the eyes 7 in operation. In view of 65 the staggered relation of the scraper ele-

ments the action is equally efficacious with respect to all parts of the circumference of the tube and the cleaning action is uniformly effective, a result attainable with difficulty in construction embodying but a 70 single element. The leather washer will push before it the loosened accumulation of mud and slime and the current of compressed air or water will blow the tube clean.

It will be seen that if the slime or mud is particularly encrusted and offers resistance greater than usually encountered by the projectile, the rod may move forwardly under the propelling force while the scraper elements remain stationary, whereby the scraper elements would be forced backwardly with respect to the rod toward the plane in which the eye 7 is secured in place. The pressure of the scraper would thus be increased peripherally against the tube tending to divide the mud or slime and by virtue of the restoring tendency of the spring resulting from the deflection thereof, pressure would be brought to bear against the accumulation to assist the propulsive force. Thus, the tube will be cleaned in an efficient manner, although no sharp cutting edges are applied.

The wire scraper extending forwardly 95 in a helix of low pitch, the wire being round in cross-section, and the helix extending about the rod for less than a complete turn, no buckling, breaking or jamming will take place as might occur if a flat ribbon wire 100 arranged in a helix of high pitch were used as a scraper element.

By reason of the material clearance between the effective length of the scraper and the rod, the scraper can be deflected through 105 a material range toward the rod, which renders possible the turning of relatively sharp corners, without likelihood of obstruction or jamming.

It is, of course, understood that the means 110 for securing the scraper elements with respect to the rod might be used for securing scraper elements of a wide variety of types, and that my specific preferred scraper elements might be secured in place by means 115 other than that set forth, also that wire of non-circular cross-section might be employed. I prefer, however, to employ the specific combination shown and described.

I claim:

1. A tube cleaning projectile of the class described, comprising in combination, a rod, a series of similar scraper elements rigidly held at an end with respect to said rod, the ends of successive scraper elements being 125 staggered with respect to each other circumferentially of the rod, the length of said elements extending free of said rod from said second end in a direction circumferentially of said rod, the scraper elements 130

being spaced from each other longitudinally of the rod, the entire length of each scraper element being intermediate the adjacent scraper elements at opposite sides thereof.

5. 2. A tube cleaning projectile of the class described, comprising in combination, a core, a series of similar metallic scraper elements coiled about said core, each secured at one end with respect to said core and free therefrom at the other end, said scraper elements being uniformly spaced longitudinally of the core and being staggered with respect to each other.

10. 3. A tube cleaning projectile of the class described, comprising in combination, a rod, a series of similar scraper elements in staggered relation equidistantly spaced along the length of said rod and secured with respect thereto, each said scraper element comprising a single wire, the length of which extends circumferentially for a small fraction of the length of said rod.

15. 4. A tube cleaning projectile of the class described, comprising in combination, a core, a series of similar, equidistant, uniformly staggered scraper members, each said member comprising a wire secured at one end with respect to said rod and extending in a free spiral thereabout, said wires being 20 secured at uniform intervals along the length of the core.

25. 5. In a tube cleaning projectile of the class described, in combination, a rod, a series of equidistant scraper elements extending 30 outwardly therefrom spacer elements encircling said rod to maintain said scraper elements at uniform distances, and a clamping member at an end of said rod for maintaining the parts in assembled relation.

35. 6. In a tube cleaning projectile of the class described, in combination, a rod, a series of scraper elements extending at right angles thereto, and spacer nuts threaded to

said rod, each said scraper element being clamped in position between two of the 45 spacer nuts.

7. A tube cleaning projectile of the class described, comprising in combination, a rod, a plurality of nut members threaded thereon, wire scraper elements encircling said 50 rod and extending outwardly therefrom and about said rod, said scraper members being clamped in position by said nuts.

8. The combination set forth in claim 7 in which each scraper element is formed of 55 a length of wire extending in a low pitch helically in advance of the plane at which it is clamped in position, the entire length of each wire being disposed between the adjacent wires at opposite sides thereof.

10. 9. In a tube cleaning projectile of the class described, in combination, a rod, a series of nuts threaded thereon, scraper elements clamped between successive nuts, each said 60 scraper element comprising a length of 65 wire encircling said rod and clamped in place by the nuts on opposite sides thereof and extending in a spiral path about said nuts, the free end of each said scraper being in advance of the secured end, the entire 70 length of each scraper element being disposed between adjacent scraper elements on opposite sides thereof, the free ends of said scraper being staggered.

15. 10. As an article of manufacture, a 75 scraper element for projectiles of the class described, comprising a length of wire coiled into a spiral, having an eye at its inner end, the spiral portion beyond the eye extending through less than a single turn and extending out of the plane of the eye in a 80 helix of low pitch.

Signed at New York city in the county of New York and State of New York this 11th day of January, A. D. 1921.

MARK K. BOWMAN.
